UNITED STATES PATENT OFFICE.

GEORGE I. TUTTLE, OF AURORA, ILLINOIS.

WATCH-REGULATOR.

SPECIFICATION forming part of Letters Patent No. 308,448, dated November 25, 1884.

Application filed May 24, 1884. (Model.)

To all whom it may concern:

Be it known that I, GEORGE I. TUTTLE, of Aurora, in the county of Kane and State of Illinois, have invented a new and useful Improvement in Watch-Regulators, of which the following is a full, clear, and exact description.

The object of my invention is to provide a regulator that will allow of the finest and most accurate adjustment, and one that can be readily used without risk of injury to the parts of the watch.

It consists in a dial, pointer, and pinion carried by the arm of the regulator, and a curved rack attached on the watch-plate, and also in certain details of construction, as hereinafter described and claimed.

Reference is to be had to the accompanying drawings, forming a part of this specification, in which similar letters of reference indicate corresponding parts in all the figures.

Figure 1 is a face view of a watch-plate with my improved regulating mechanism. Fig. 2 is a cross-section on line $\alpha\alpha$ of Fig. 1, and Fig. 3 is a back face view of the regulator-arm. These figures are in enlarged size.

A is the watch-plate. a is the regulator-arm, hung on the balance-bridge b , as usual. On the outer end of the arm is fixed a graduated dial, c , of circular form, that carries an arbor at its center, and on the arbor beneath the dial is a pinion, d . On the arbor and above the dial is a pointer, e .

f is a curved rack of suitable length, attached at one end to plate A by a screw, g , and h is a spring attached to the plate and bearing on the free end of the rack, so as to retain the same in mesh with pinion d at all times, while allowing a certain amount of elasticity. The rack-plate has a graduated scale

on its face for indicating the extent of movement of arm a , the end of which extending over the rack is pointed. The scale on dial c indicates divisions of the spaces on the dial-scale to a fine degree.

In order to operate the regulator the pointer e is turned by using any simple instrument, and the pinion turning on the rack causes arm a to travel in either direction, as the case may be. The movement of the pointer will be considerable to obtain a slight movement of the regulator-arm, so that fine adjustment is possible, and the extent of movement is determined by the scale. It is to be observed that the dial is at a distance from the balance, so that there is no risk of injuring the spring or wheel. If desired, the rack may be on the balance-bridge, and equally removed from the vicinity of the balance.

Having thus described my invention, I claim as new and desire to secure by Letters Patent—

1. In a watch-regulator, the combination, with the rack f , secured to the watch-plate, of the dial c , secured on the outer end of the regulator-arm, the pinion d , and the pointer e , the pinion and pointer being upon an arbor at the center of the dial, substantially as herein shown and described.

2. In a watch-regulator, the combination of pinion d and pointer e , carried by the regulator-arm, and the rack f , substantially as shown and described.

3. In a watch-regulator, the pivoted rack f and spring h , combined with the regulator-arm and pinion thereon, substantially as described.

GEORGE I. TUTTLE.
